United States Patent Office.

MILTON V. NOBLES, OF ELMIRA, NEW YORK.

Letters Patent No. 63,081, dated March 19, 1867.

IMPROVED BOAT-DETACHING TACKLE.

The Schedule referred to in these Letters Patent and making part of the same.

TO ALL WHOM IT MAY CONCERN:

Be it known that I, MILTON V. NOBLES, of Elmira, in the county of Chemung, and State of New York, have invented certain new and useful Improvements in Boat-Detaching Apparatus; and I do hereby declare the following to be a full, clear, and exact description of the construction and operation of the same, reference being had to the accompanying drawings, making a part of this specification, in which—

Figure 1 represents a top plan of a life or other boat with my apparatus attached.

Figure 2 represents a side view with portions of the connecting and disconnecting apparatus in dotted and portions in full lines.

Figure 3 represents a section through the boat and showing the apparatus at one end thereof in elevation, and by black and red lines, its connected and disconnected positions.

Figure 4 represents a modification of the plans shown in the other figures

Similar letters of reference, where they occur in the several separate figures, denote like parts in all the drawings.

The liability of boats to tip, when suspended at points at or near the centre longitudinally, from the haste or emergency in which they are detached, and the unequal distribution of the weight of the passengers or load therein, frequently causes great loss of life. My object and purpose are to disconnect as readily as is done by the single central supports, but at the same time avoid the casualty incident thereto by preventing the tipping of the boat.

My invention consists in combining with the detaching apparatus, whether arranged at or over the centre or the sides of the boat, a bail, bar, or other cross-piece extending to and connected with the sides of the boat, so as to act as a brace against the tendency of the boat to tip when hastily or unevenly loaded.

To enable others skilled in the art to make and use my invention, I will proceed to describe the same with reference to the drawings.

At the bow and stern of the boat I connect transversely a bail, A, as seen in figs. 1, 2, 3, by dead-eyes or hinges, *a a*, so that when not connected to the davit-blocks they may swing over and lie upon the boat and be out of the way. To the crown or central portion of these bails is fastened a pillar or standard, B, to the top of which is pivoted a hook or bent lever, *b*, and below the hook or lever there is also pivoted an arm or trigger, *c*, into an opening in which the point of the hook takes, (as shown in fig. 3,) and holds when the boat is suspended to the tackle. To the end of the arm *c* is hinged or pivoted the upper end of a rod, *d*, which is slotted so as to straddle the bail, and has, moreover, a hinge-joint, *e*, so that it can swing with the bail when the latter is laid down or raised up. The lower end of this rod is pivoted to a crank-arm, *f*, attached permanently on the longitudinal bar or rod *g*, extending along near the bottom of the boat, and from one disconnecting device at one end to another at the other end of the boat. The rod or bar *g* is rocked by a lever, *h*, in one direction to throw in the connecting apparatus, as shown by black lines, and in the opposite direction to disconnect, as shown by the red lines in fig. 3. The boat need not necessarily be suspended by its sides which might strain it, as a rod, *i*, (also hinged to swing with the bail,) may extend from the centre of the bail down to or through the keelson or keel, and lift from that part of the boat which is the most rigid. To prevent the bails from swinging in towards the centre of the boat when suddenly disconnected, a piece of rubber or other spring, *j*, may press against them to drop them upon the decks at the ends. In fig. 4 I have shown a modification of this general plan, where the detaching hooks *m* are at the sides of the boat, and two in number. From these hooks a bail or strap may extend to the davit-blocks or other tackle to suspend the boat, and when disconnected, this bail or strap would go with the tackle and not with the boat as in the other figures. The hooks *m* may be simultaneously disconnected by the rocking of the shaft *n*, which can be done from the main shaft and lever through a link, *o*. When much weight comes upon any of the moving parts friction-pulleys can be used to relieve them.

What I claim as my invention, is—

1. In combination with a boat-detaching apparatus, a bail, bar, or brace, connected to the side of the boat so as to prevent the boat from tipping when unevenly loaded, substantially as described.
2. I also claim hinging the bails by which the boat is steadied at the sides, so that when let go or disconnected they will drop and lie upon the decks, and thus not incommod or endanger the passengers or crew as described.
